Inventor:

Vojtěch Urbanides

UNITED STATES PATENT OFFICE.

VOJTECH URBANIDES, OF KÖNIGSAAL, NEAR PRAGUE, AUSTRIA-HUNGARY.

HOOK FOR BEDSTEADS, DOORS, AND THE LIKE.

1,126,133.

Specification of Letters Patent.

Patented Jan. 26, 1915.

Application filed March 6, 1914. Serial No. 822,970.

To all whom it may concern:

Be it known that I, VOJTECH URBANIDES, a subject of the Austro-Hungarian Emperor, and resident of Königsaal, near Prague, Bohemia, Austria-Hungary, have invented certain new and useful Improvements in Hooks for Bedsteads, Doors, and the like, of which the following is a specification.

10 This invention relates to a hook which is provided with a peculiar device which prevents it from opening spontaneously and is especially suitable for use as a fitting in connection with bedsteads, as well as with doors of railway carriages.

The accompanying drawing shows three forms of embodiment of the invention.

Figure 1 is a side elevation of the device. Fig. 2 is a section through the locking members. Fig. 3 is a modification. Fig. 4 is a section through the locking members of Fig. 3. Fig. 5 is a further modification. Fig. 6 is a section through the locking member of Fig. 5.

25 The hook *a* is mounted in the usual manner so as to be able to turn around a stud of the plate *b*; its hook shaped end engages the eye 2. According to the present invention the plate *b* (Figs. 1 and 2) is 30 provided on one side with a recess 3, whereby a tongue is formed, which by stamping is converted into a spring *c* provided with a ball shaped projection 4. The hook *a* is provided with a stamped ball depression 5, 35 into which the projection 4 of the spring *c* snaps when the hook is in its closed position (shown in dotted lines). The hook is provided on its lower side with an out turned lug 6, so that it may pass over the 40 projecting part 4 of the spring, during its closing motion. In order to open the hook an upward pressure is exerted upon the latter in the direction of the arrow I, whereby the projection of the spring is caused to 45 leave the depression of the hook, thus allowing the hook to be lifted.

The form of the invention shown by Figs. 3 and 4 differs from the one described in that the spring *c*, instead of being provided 50 with a projection carries a tooth 4', and the

hook *a* has an aperture 8 surrounded by the stirrup 7 so that during the closing of the hook, the inclined wall 6 of the latter pushes aside the tooth 4' until it snaps into the hole 8 owing to the action of the spring. 55

For opening the hook pressure is exerted upon the tooth 4' until it is disengaged from the hook *a* thus allowing of the latter being rotated.

The form of embodiment shown by Figs. 60 5 and 6, is particularly suitable for doors of railway carriages and the like. Spring *c* is directed downwardly and extended on a short distance so that it can be easily pushed inwardly by means of the hand. 65

In all the forms of this invention, the accidental opening of the hook is avoided because the spring *c*, which is protected does not allow of this movement, besides, the devices forming the subject matter 70 of this invention is simple and suitable as a fitting for bedsteads and can be manufactured by stamping.

Having now fully described my said invention, what I claim and desire to secure 75 by Letters Patent, is:

1. In a device of the character described, the combination with a hook member, of a plate, means for pivotally mounting said hook, a spring tongue formed in said plate, 80 a head on said tongue, means carried by said hook adapted to engage said head, and means carried by said hook for guiding said spring tongue.

2. In a hook of the kind described, the 85 combination with the hook proper provided with an aperture therein, of a plate, means for pivotally connecting the said hook with said plate, a downwardly projecting spring struck out from the said plate, a projecting 90 tooth struck out from the said spring and adapted to engage the said aperture of the hook, substantially as and for the purpose set forth.

In testimony whereof I have hereunto set 95 my hand in presence of two witnesses.

VOJTECH URBANIDES.
